FIG. 4.

UNITED STATES PATENT OFFICE.

WALTER EMMETT AIREY AND JOHN POMFRET, OF MANCHESTER, ENGLAND.

UMBRELLA.

1,373,642.

Specification of Letters Patent.

Patented Apr. 5, 1921.

Application filed December 30, 1919. Serial No. 348,369.

To all whom it may concern:

Be it known that we, WALTER EMMETT AIREY and JOHN POMFRET, subjects of the King of Great Britain and Ireland, residing, respectively, at "Copper Beeches," Fog Lane, Didsbury, Manchester, in the county of Lancaster, England, and 44 Greenhill road, Manchester, aforesaid, have invented new and useful Improvements in Umbrellas, 10 of which the following is a specification.

The invention relates to improved means for preventing waterlogging, and for securing means for ventilation, in and about the top notch and outer ferrule cover of umbrellas, to prevent the premature disintegration, 15 rotting, and wearing of umbrella covers at this point. This premature disintegration, wearing and rotting is caused by the fabric at this part becoming waterlogged, as generally the umbrella is left standing when 20 wet, and the water gravitates to this end of the cover, and owing to its being so closely folded at this part, air has no chance to act upon it to dry it quickly.

Our object is to construct and mount the top notch and outer ferrule in such a manner as will provide holes, channels or passages to allow for the rapid drainage of the water, such passages also providing means to insure a free air circulation to the wet fabric 30 to assist in promptly drying same. This we do by providing the top notch or barrel with internal and external longitudinal grooves, recesses or channels. We also provide the 35 outer ferrule with drainage holes to allow for the drainage of the water.

The invention, which we will describe in detail, is illustrated in the accompanying drawings, in which,

Figure 1 is a sectional elevation of the improved umbrella fitting.

Fig. 2 is a plan thereof, and,

Figs. 3 and 4 show in plan and elevation respectively a modification of the fitting.

In carrying our invention into effect we form the top notch and barrel *a*, as usual, 45 separate from the outer ferrule, the umbrella ribs being secured at *a'*. The top notch and barrel *a* is made a tight fit upon the umbrella stick *b* which is shown in dotted lines. The top notch and barrel *a* is formed internally with longitudinal recesses *c* and is provided with slits *d* from the bottom 50 a short distance upward, and is screw threaded externally. On this top notch and

barrel *a* is screwed the outer ferrule *e* the end of the ferrule having holes *e'* bored therein. The outer ferrule *e* is made at the bottom a tight fit upon the umbrella stick. Water entering the interior of the top notch 60 *a* will drain down the channels or recesses *c* into the outer ferrule *e* and away through the holes *e'*. Also water can drain away between the top notch *a* and outer ferrule *e* along the channels or grooves *d'*, through 65 the slits *d*, and out through the holes *e'*. This allows for the prompt drainage of the cover when wet, but also such channels or recesses, and holes, provide means for air to circulate and have access to the cover and 70 insure its being dried quickly.

The Figs. 3 and 4 show a variation of the constructions already described.

In this arrangement the top notch or barrel *a* is formed with internal ribs *a²* which 75 produce longitudinal channels or grooves and with longitudinal external grooves *a³*. The top notch or barrel in this instance is not screw threaded, the top notch, and the surrounding outer ferrule *e* being each secured to the umbrella stick by any convenient means. The internal ribs *a²* and external grooves *a³* produce longitudinal channels which permit of the drainage of water internally and externally from the top notch 85 or barrel *a* into the outer ferrule *e* which is drained by means of the holes *e'* as described.

We declare that what we claim is:

1. In an umbrella, a notch provided at 90 its interior with a plurality of longitudinal channels, and a ferrule encircling said notch and having radial openings communicating with the interior of the ferrule, said longitudinal channels of the notch also communicating with the interior of the ferrule.

2. In an umbrella, a notch provided at its interior with a plurality of longitudinal channels, and also provided with a plurality of radial slots, said notch being exteriorly threaded for a portion of its length, and an interiorly threaded ferrule secured to said notch and provided with a plurality of radial openings, the longitudinal channels and radial slots of the notch communicating with the interior of the ferrule. 100 105

In testimony whereof we have signed our names to this specification.

WALTER EMMETT AIREY.
JOHN POMFRET.
